DELOS P. HEATH, OF GRAND RAPIDS, MICHIGAN.

REFRIGERATOR AND REFRIGERATING APPARATUS THEREFOR.

Application filed April 6, 1925. Serial No. 20,912.

REISSUED

This invention relates to a refrigerator construction including a refrigerating apparatus and its installation in a box or case whereby the apparatus performs the combined functions of a vertical partition to divide the box into compartments, serves as a support for the shelves used, and absorbs heat to thereby cool the interior of the box.

One primary object and purpose of the present invention is to provide a refrigerating unit which, when installed in the refrigerator box, serves as a vertical partition for the same doing away with the usual partial vertical partition required in refrigerators and so constructing the unit that the part thereof which serves as the partition may be located at any desired point so as to divide the box into compartments of either equal or different sizes and to seal them from each other.

A further object of the invention is to construct a refrigerating unit which may be made, assembled and charged at its place of manufacture, with the manufacture of boxes in which it is to be installed at another place or factory, the refrigerating unit being capable of shipment while in completely assembled and charged condition and then readily installed in the refrigerator boxes.

A still further object of the invention and one of importance resides in the construction of the refrigerating unit and particularly in the tank construction thereof, which is of novel form and comprises many novel features of construction and arrangement of parts whereby it is capable of a variety of uses. For instance the tank itself may be used in other places than as a part of a refrigerating mechanism though its construction is very well adapted for such refrigerating use.

Many other objects and purposes than those specifically stated will be apparent as an understanding of the invention is had from the following description taken in connection with the accompanying drawings, in which,

Fig. 1 is a perspective view, with some parts broken away and in section, showing a refrigerator equipped with refrigerating apparatus and installed therein in accordance with my invention.

Fig. 2 is an enlarged central vertical section taken through the upper portion of the tank.

Fig. 3 is an enlarged side elevation of said tank.

Fig. 4 is a front elevation thereof.

Fig. 5 is a front elevation of a detail of construction relating to a plate adapted to close the front end of the upper part of the tank.

Fig. 6 is a fragmentary horizontal section taken on the plane of line 6—6 of Fig. 9.

Fig. 7 is a fragmentary transverse vertical section through the upper portion of the tank.

Fig. 8 is a similar section through the lower portion thereof.

Fig. 9 is a fragmentary vertical section taken on the plane of line 9—9 of Fig. 8.

Fig. 10 is a fragmentary horizontal section on the plane of line 10—10 of Fig. 8.

Fig. 11 is a front elevation of a slightly different form of refrigerator construction using the same invention.

Fig. 12 is a fragmentary enlarged front elevation of the construction shown in Fig. 11, the doors and front panel being removed, and

Fig. 13 is a fragmentary plan view of a slight modification in the construction for passing the refrigerant carrying pipes.

Like reference characters refer to like parts in the different figures of the drawings.

The refrigerator box 1 may be, generally, of any desired construction and is equipped with a horizontal partition 2, some distance above its lower end in one front corner of which a notch or recess 3 is cut, as shown. Below this partition the front of the refrigerator is closed by a removable panel 4 at the upper portion of which is a removable cross rail 5 adapted to be secured in place. The front of the refrigerator above said rail 5 is adapted to be closed by doors which may be opened for access to the compartments above the partition 2.

In the construction of the refrigerating apparatus a tank is provided having an inner shell of sheet metal with spaced apart vertical sides 6 integrally connected by an arch 7, best shown in Fig. 7. A short distance below this arch a plurality of spaced apart horizontal ribs 8 are pressed inwardly from each side 6 preferably of the shape shown which, as will later appear, serve a number of functions in the construction. Also near their lower edges the sides 6 are formed with inwardly pressed horizontal

beads 9. At the back this inner shell structure is closed by a back plate 10 and at the bottom by a bottom plate 11, the front being open.

5 Over the inner shell structure thus made, an outer shell is located being formed from a single plate of sheet metal and with alternate outwardly pressed ribs or corrugations 12 and connecting sections 13 between. This 10 outer shell is formed into substantially U-shape with its arch located a distance above the arch 7, making a chamber 14 at the upper end of the tank between the two arches. The outer shell is permanently connected to 15 the inner shell by welding the sections 13 and the flanges 13^a at the edges of the other shell to the side plates 6 of the inner shell. It will be noted that the bottom 11 is formed with up-turned side flanges 11^a and 20 that the lower edges of the outer shell pass within the same and lie against the lower portions of the sides 6, these parts being securely welded together. At the rear end of 25 the tank the space between the arch 7 and the arch of the outer shell is filled by a filler plate 15 (see Fig. 2) and at the front by a member 16 (see Fig. 5) in which an opening 17 is made adapted to be filled by a head 18 from which the usual pipes 19 and 30 20 for conducting the refrigerant lead to the compressor mechanism of the refrigerating apparatus used in apparatus of this character.

The chamber 14 between the arches of 35 the inner and outer shells as well as the spaces between the sides 6 of the inner shell and the outwardly pressed corrugations 12 of the outer shell are adapted to receive the refrigerant which may be of any desired 40 type. The level of the refrigerant is controlled by the usual float 21 shown in Fig. 2. The mechanism relating to the compressor and the control of the refrigerant, as it forms no part of the present invention, 45 is not described in detail. Inasmuch as the pressure within the chamber 14 and to which the refrigerant is subjected is high at times the structure has to be of considerable strength and at the same time should 50 not be very heavy or bulky. With the corrugated outer shell shown this strength is obtained, and to brace and strengthen the inner shell the inwardly pressed ribs 8 and 9 as well as the arch construction at 7 are 55 provided. In addition it will be noted that the ribs 8 and beads 9 make connections between the various spaces enclosed by the outward corrugations 12 so that there is a free circulation permitted of the refrigerant. 60 The inner shell 6 may be used for storage or for various other purposes. For instance in the upper portion of the shell a semi-circular trough 22 is located and welded in place, making a substantially circular compartment at the upper end. Below this com- 65

partment a number of trays 23 are mounted, being supported on the inwardly extending ribs 8, which serve this additional function beside that of strengthening and reinforcing the inner shell and providing circulation passages for the refrigerant. And in the lower end of the shell a storage compartment indicated at 24 may be utilized. The upper compartment above the trays 23 is adapted to have its front end closed by 70 a removable cover 25 and in this various articles of food or drink may be placed and the same is true with respect to the lower compartment at 24. In the trays 23, if desired, water may be placed for the production of ice.

In order to facilitate cleaning the refrigerant holding chamber and spaces the front ends of each bead 9 may be equipped with a sleeve 26 into the front end of which a plug 27 is screwed adapted to be removed for cleaning the tank should this become necessary. This is likely to happen but rarely when the device is used in refrigerating apparatus but it is evident that the tank 90 construction is capable of use in other relations, as for instance in a boiler or as a steam or hot water radiator wherein cleaning out is of much greater importance. In fact this construction and its use in connection with refrigerating apparatus is technically a boiler, the refrigerant in liquid form boiling and evaporating readily with the reduction of pressure thereby absorbing heat from the outside and reducing the temperature of the surrounding parts, hence the refrigerating action and result.

The tank as thus constructed is adapted to be located vertically in the refrigerator box and as one means of locating and securing it in place it is equipped with upwardly and downwardly extending angle brackets 28 at its upper and lower ends. Also at a number of points at its sides shelf supports 29 are secured and extend outwardly. Suitable suspension members 30 attached to the upper side of the refrigerator compartment and connected with the upper brackets 28, and other supports 31 secured to the horizontal partition 22 and connected in any suitable 105 manner with the lower brackets 28 locate the tank in place and hold it in desired position. It is evident that the tank may be located midway between the sides of the refrigerator box or closer to one side than the 110 other and also that there are open spaces both above and below the tank for the free circulation of air in the compartment. Shelves 32 of usual type may be carried on the shelf supports 29 on the tank and on like 115 supports projecting inwardly from the vertical sides of the refrigerator box.

When installed in a refrigerator the pipes 19 and 20 pass below the partition 2, the recess or notch 3 permitting this passage and 120

below this partition and back of the panel 4 is the usual compressor construction required with refrigerating devices of this character. The pipes 19 and 20 are of flexible material, 5 such as copper, and it is not only possible but very feasible with the exercise of proper care to assemble the entire refrigerating unit and charge the same, and then ship the unit in charged and operative condition any 10 distance desired to a refrigerator factory where the boxes are made, the flexible pipes 19 and 20 being coiled in connection with the tank and compressor so as to occupy the least space. Then when the refrigerating 15 unit reaches its place of installation, the pipes are uncoiled and straightened and shaped into proper shape for installation. The panel 4 and rail 5 being removed the insertion of the refrigerating unit into the refrigerator is very readily accomplished, the panel 4 and rail 5 being replaced and the rail secured in place.

In Figs. 11 and 12 a slightly different form of installation in a refrigerator is shown and 25 which is preferred. The refrigerator 1 has the same horizontal partition 2, front panel 4, said cross rail having a notch 3^a therein through which the pipes 19 and 20 may pass equivalent in all respects to the notch 3 in 30 the partition 2 first described. At the front of the refrigerator a panel 33 is located in front of the tank and fitting against the same so as to be substantially tight. On this panel a hinged door 34 is mounted, the purpose of which is to gain access to the various 35 compartments at 24 and 25 and the trays 23. Instead of the brackets 28 and the supports 30 and 31 being used to mount the tank, plates 35 and 36 at the upper and lower ends 40 of the tank extending the full depth of the refrigerator are used. This divides the refrigerator into two entirely separate and independent compartments. It will be noted that the tank is located closer to one side 45 of the refrigerator than the other and it will be evident that as the refrigerating action of the tank on one compartment is the same as in the other, the smaller compartment will be held to a lower degree of temperature 50 than the larger. This is a very desirable feature in refrigerators and it is particularly desirable that various compartments in a refrigerator be had which are wholly independent and unconnected from the others. This 55 permits the placing of certain articles in one compartment and others in another in accordance with the desired temperature at which these articles should be kept. Moreover the interior space in the tank is wholly 60 independent of either compartment in the refrigerator and the several compartments in the tank are independent of each other, thereby increasing the range and number of separate storage spaces in the refrigerator, each 65 of which is independent of the other and does not have to be opened when any one of the others is opened with a loss of efficiency. The doors which are used to close the compartments, one at each side of the tank, are independently mounted and may be independently opened and closed as is evident. 70

The construction described is very practical, is of light weight but of great strength and with it iceless refrigerators may be very simply and economically produced. Of course as stated before the tank construction is not limited in use to refrigerators alone but has many features of construction adapting it for a variety of other uses. The invention is defined in the appended claims and 75 it is to be considered as comprehensive of all forms of structure coming within their scope irrespective of the particular use to which put.

I claim:

1. A device of the character described comprising, an inner shell having spaced apart sides and a connecting arch at their upper ends, an outer shell having spaced apart sides and arch located over the inner shell, said outer shell at its upper end being disposed a distance above the upper end of the inner shell and being formed with alternate outwardly projecting corrugations and intermediate connecting portions between the corrugations and permanently secured to the inner shell whereby a chamber is made between the arches of said inner and outer shells connecting with which are vertical spaces made by said outwardly extending corrugations between the same and the sides of the inner shell, means closing the said chamber at both ends thereof and a bottom plate extending between the lower edges of said shells and secured thereto, substantially as described. 85

2. In a device of the class described, the elements in combination defined in claim 1, said inner shell near the lower edges of its ends being formed with horizontally located inwardly pressed beads, and at upper portions of said sides with horizontally located inwardly pressed ribs, to thereby reinforce the inner shell and provide communicating passages between the spaces enclosed by the 90 said outer corrugations and the sides of the inner shell. 95

3. In combination in a device of the class described, an inner shell including spaced apart sides of sheet metal and an integral arch connecting portion at their upper ends, an outer shell of sheet metal also having spaced apart sides and an integral connecting upper arch portion placed over the inner shell, said outer shell being formed with alternate outwardly extending corrugations and intermediate flat connecting portions, said outer shell being pressed over the inner shell with the said connecting portions in 100 the sides of the outer shell lying against the 105 inner shell. 110

4. In combination in a device of the class described, an inner shell including spaced apart sides of sheet metal and an integral arch connecting portion at their upper ends, an outer shell of sheet metal also having spaced apart sides and an integral connecting upper arch portion placed over the inner shell, said outer shell being formed with alternate outwardly extending corrugations and intermediate flat connecting portions, said outer shell being pressed over the inner shell with the said connecting portions in 115 the sides of the outer shell lying against the inner shell. 120

5. In combination in a device of the class described, an inner shell including spaced apart sides of sheet metal and an integral arch connecting portion at their upper ends, an outer shell of sheet metal also having spaced apart sides and an integral connecting upper arch portion placed over the inner shell, said outer shell being formed with alternate outwardly extending corrugations and intermediate flat connecting portions, said outer shell being pressed over the inner shell with the said connecting portions in 125 the sides of the outer shell lying against the inner shell. 130

sides of the inner shell and with the arch of the outer shell located a distance above the arch of the inner shell, whereby said connecting portions and the sides of the inner shell may be welded together, means closing each end of the compartment between the upper ends of the inner and outer shells, a bottom plate disposed between and connected to the sides of said shells at their lower edges, and a back plate closing the rear end of the inner shell, substantially as described.

4. A construction containing the elements in combination defined in claim 3, said sides of the inner shell adjacent their lower edges being formed with horizontal inwardly pressed beads, and adjacent their upper portions with a plurality of spaced apart inwardly extending horizontally located ribs,

trays slidably mounted on said ribs, and removable means for closing the front ends of the spaces above and below said trays, substantially as described. 20

5. In a refrigerator apparatus an expansion chamber comprising an inner shell having spaced apart sides and a connecting arch at one end, an outer shell having spaced apart sides and a connecting arch at one end, said arches being spaced apart to provide an unobstructed chamber having arched top 30 and bottom, one of said shells being corrugated, said shells being welded together at contiguous portions between the corrugations and at their peripheries to form a chamber for the expansion of refrigerant. 35

In testimony whereof I affix my signature.

DELOS P. HEATH.
